US00D819126S

(12) **United States Design Patent** (10) **Patent No.:** **US D819,126 S**
(45) **Date of Patent:** **** May 29, 2018**

(54) **MULTI-USER READING COMPREHENSION THERAPY DEVICE**

(71) Applicant: **East Carolina University**, Greenville, NC (US)

(72) Inventors: **Michael Rastatter**, Winterville, NC (US); **Todd Carter**, Greenville, NC (US); **Mark Allen**, Highlandville, MO (US); **Ricardo Rodriguez**, Raleigh, NC (US); **John Trainor**, Morrisville, NC (US)

(73) Assignee: **East Carolina University**, Greenville, NC (US)

(**) Term: **14 Years**

(21) Appl. No.: **29/502,230**

(22) Filed: **Sep. 12, 2014**

Related U.S. Application Data

(63) Continuation of application No. 29/441,307, filed on Jan. 3, 2013, now Pat. No. Des. 716,375.

(57) **CLAIM**

The ornamental design for a multi-user reading comprehension therapy device, as shown and described.

DESCRIPTION

FIG. 1 is a side perspective view of a multi-user reading comprehension therapy device, showing our design; FIG. 2 is a top view thereof; FIG. 3 is a front view thereof; FIG. 4 is a bottom view thereof; FIG. 5 is a rear view thereof; FIG. 6 is a right side, in the orientation of FIG. 2, view thereof; FIG. 7 is a left side, in the orientation of FIG. 2, view thereof; FIG. 8 is a front perspective environmental view thereof; and, FIG. 9 is a top side different environmental view thereof. The broken lines in the drawings are for purposes of illustrating portions of the multi-user reading comprehension therapy device, as well as environmental structure, which form no part of the claimed design.
